UNITED STATES PATENT OFFICE.

ROBERT REACH, OF WASHINGTON, DISTRICT OF COLUMBIA.

BLAST-LAMP.

SPECIFICATION forming part of Letters Patent No. 269,110, dated December 12, 1882.

Application filed April 4, 1882. (No model.)

To all whom it may concern:

Be it known that I, ROBERT REACH, a citizen of the United States, residing at Washington, in the District of Columbia, have invented a certain new and useful Improvement in Blast-Lamps, of which the following is a specification, reference being had therein to the accompanying drawings.

My invention relates to an improvement in blast-lamps; and it consists in the combination and arrangement of the parts, as herein-after more fully shown and described.

In the drawings, Figure 1 is a central section. Fig. 2 is a perspective of the lamp-kit, the dotted lines showing position of lamp when being conveyed. Fig. 3 is a side elevation, showing shield and cap as applied for painter's use. Fig. 4 is a front view of vapor-chamber, and Fig. 5 is a detail view of check-valve.

A represents an oil-tank, which is preferably cast in one piece, and provided with the filling-orifice a. The tank has inserted therein, and projecting through a closed orifice in the cap F, the vertical tube C', connecting with the asbestos conduit C. Egress of the oil contained in the tank or vapor arising therefrom is regulated by the cock-valve f where it intersects the asbestos conduit C. The asbestos conduit C is packed with asbestos near the cock-valve f and at the elbow f', which effectually prevents the oil from being forced too rapidly by the pressure of atmosphere in the top of the oil-tank into the vapor-generator. 35

In this connection I would state that I deem Danforth's patented non-explosive oil the only reliable non-explosive burning-fluid, and that I use it exclusively for my blast-lamp.

40 The air-tube is provided with the mouth-piece e, and through this tube air is blown from the mouth into the tank.

In Fig. 1 is shown the altitude of the oil with which the tank is supplied, the altitude thereof at all times admitting an air and vapor chamber above it. Air being blown into the tank, the oil and vapor are forced into the vapor-generator E, the check-valve b', as shown in Fig. 5, preventing the escape of the gas 45 from the air-tube when the blowing ceases.

The grate G has its bearings upon the inclined walls of the lamp-kit B. The lamp-kit

is provided with the door H, through which the soldering-irons are thrust when placed on the grate to be heated by the flame from the 55 burner or orifice h. The lamp-kit has also formed therein the vertical slot I, through which projects the vapor-burner when the lamp is placed in the kit, as shown by the dotted lines in Fig. 2, to render it portable. Thus it 60 will be observed that the lamp-kit not only serves to render the blast-lamp conveniently portable, it being provided with the handle K, but that it also serves as a means of elevating the grate above the flame of the burner for 65 heating the soldering-irons.

When such ordinary heat is required to be generated as is generally used by artisans the vapor proceeding from the orifice or burner h and thrown upon the grate G will produce sufficient flame for the intended purpose. Such a flame will be found ample to keep in proper heated condition the soldering-irons of tanners and plumbers, and my blast-lamp is especially adapted for such use, as it presents many obvious advantages over the slow and more expensive method of heating soldering-irons by charcoal. 75

The shield D, slightly curved, is a piece of thin metal secured at the top of the vapor-generator in recess d' by the thumb-screw d'', and projecting horizontally therefrom. 80

To the lower part of the vapor-generator E is pivoted the cup d, which is designed to catch the drippings of oil which are blown 85 from the orifice of the burner h, and when an intense heat or enlarged flame is desirable the oil blown through the orifice of the burner, and which is caught in the oil-cup, is set on fire, and the flame arising therefrom heats the 90 vapor-generator, and thus greatly increases the quantity of flame generated and proceeding from the burner.

In scorching off old paint the artisan discards the lamp-kit and holds the lamp by the 95 handle N, which is screwed into a female screw provided in the wall of the oil-tank, and thus secured it may be removed when not needed. The vapor-generator is formed of the slightly curved metallic disks g and g', the periphery 100 of the disks being united together, and in the center thereof having horizontal orifices, wherein are secured the asbestos conduit C and the burner h. The clamp a', having re-

cess d' for the reception of the shield D, is also provided with a vertical threaded orifice, wherein is located the thumb-screw d'' for holding the shield. This shield is employed as a means of diffusing a flame over a large surface, and when it is employed the oil is blown into the vapor-generator E, and the flame proceeding from the burner h heats the fluid in the vapor-generator and rapidly vaporizes it, and thus greatly enlarges the volume of flame, proceeding from the burner, and the flame in its ascent from the burner, is spread over a large surface by means of the shield. This method of employing my device will be found very useful in the ordinary process of removing paint preliminary to repainting, which is the custom of coach-makers and others.

By this construction of my blast-lamp it will

be observed that provision is made for regulating the extent of the flame and the degree of heat which may be produced, the asbestos packing preventing a too great flow of the fluid under air-pressure, and that the device may be usefully employed in many of the arts.

Having thus described my invention, what I claim, and desire to secure by Letters Patent, is—

The combination of the oil-tank A, having orifice a, lamp-kit B, having grate G, door H, and vertical slot I, substantially as shown, and for the purpose described.

In testimony whereof I affix my signature in presence of two witnesses.

ROBERT REACH.
